AUTOMATIC VACUUM REGULATOR

Jacob Henry Lienau, New York, and Jacob John Neuman, Jamaica, N. Y.

Application February 1, 1933. Serial No. 654,693

7 Claims. (CL 257—2)

This invention relates to an automatic vacuum regulator, and has for its primary object and purpose to provide simple and reliably operating apparatus for automatically maintaining a substantially uniform predetermined vacuum in the operation of evaporating apparatus, such for instance as is used in the refining of raw sugar.

As is well known, in the processing or refining of sugar, it is necessary to boil the raw sugar liquor in vacuum pans, and it is generally desirable to maintain the vacuum in the pan more or less constantly uniform during the evaporation step of the process. Heretofore, this has generally been accomplished through manual control, 10 requiring almost constant attention, and attended by rather poor results.

It is accordingly an important object of the present invention to provide an automatically operating vacuum regulating or control means 20 whereby this dependence upon manual attention with its accompanying uncertainties in the proper control and regulation of the vacuum is eliminated.

The invention of the present application is 25 more particularly designed and intended for use in connection with evaporating apparatus of that type, wherein the vacuum is produced by the condensation of the vapors evolved in the boiling of the sugar liquor in the vacuum pan, another important object of the invention being to effect a 30 material saving in the use of condensing water.

Another object of the invention is to provide an automatic apparatus for the above purpose, the use of which will result in the production of a 35 higher standard of quality of the refined product, and the several cooperating parts of which are of such construction that the improved control means is readily applicable to evaporating apparatus of the kind now in general use without necessitating any appreciable mechanical changes 40 thereof.

With the above and other objects in view, the invention consists in the improved vacuum regulating apparatus, and in the form, construction 45 and relative arrangement of its several parts, as will be hereinafter more fully described, illustrated in the accompanying drawing and subsequently incorporated in the subjoined claims.

In the drawing wherein we have illustrated 50 several simple and practical embodiments of the present invention, and in which similar reference characters designate corresponding parts throughout the several views,—

Figure 1 is a semi-diagrammatic view illustrating an electrically operated vacuum control

means as applied to a conventional type of evaporating apparatus; and

Fig. 2 is a similar view showing an alternative embodiment of the invention wherein a fluid pressure actuated control means is employed. 60

Referring in detail to the drawing, and for the present more particularly to Fig. 1 thereof, 5 indicates the conventional type of vacuum pan having a connection 6 at its upper end to the condenser 7, which is supplied with water through 65 the pipe connection 8 in which the water supply regulating valve indicated at 9 is arranged. Thus it will be understood that water supplied to the condenser 7 condenses the vapors rising from the boiling liquor in the vacuum pan 5, the 70 vacuum maintained in said pan being proportionate within certain limits to the quantity of water which is discharged into the condenser while the liquor is boiling. Therefore, it will be evident that by adjusting the valve 9, the degree 75 of vacuum maintained in the pan 5 will be varied or regulated.

In Fig. 1 of the drawing, we have shown an operating means for the valve 9 consisting of a reversible electric motor 10 operatively connected 80 through suitable reduction gearing to the endless chain 11, engaged with the sprocket 12 fixed to the shaft or spindle of valve 9.

The operation of the motor 8 in the proper direction is controlled through the control panel 85 indicated at 13, to which current is supplied through the connections 14 from any convenient source of current.

A vacuum gauge shown at 15 is connected with the pan 5, said gauge having the indicator hand 90 16 responsive to variations in the vacuum and which is actuated by a Bourdon tube or other suitable means. The relatively stationary hand 17 of the gauge is manually adjustable with respect to the gauge scale and may be set in accordance with the desired predetermined vacuum 95 to be maintained in the pan 5. These gauge hands are suitably insulated from each other, and provided at their outer ends with circuit closing contacts. In the circuit connections 18 100 between the gauge hands and the control board 13, a suitable type of reversing switch mechanism 19 is interposed and may be adjusted by the hand wheel 20 for either manual or automatic operation. Since the details of this switch mechanism constitute no essential part of our present invention, it is not herein further described.

Also, the details of the control board 13, are not essential to a clear understanding of the present invention, and it is apparent that various means 105 110

might be employed for closing the circuit of motor 10 in one direction when the contacts of the gauge hands 16 and 17 come into engagement with each other and for closing said circuit in the 5 opposite direction when said contacts separate from each other.

In the operation of the evaporating apparatus, the vapors rising from the vacuum pan 5 are 10 condensed by the cooling water supplied to condenser 7, and when this vacuum reaches the predetermined point for which the gauge hand 17 has been set, the contact thereof is engaged by the contact of the gauge hand 16 to close the circuit of motor 10 and move the chain 11 in the proper 15 direction to move the valve 9 towards its closed position, and thus reduce the flow of cooling water to the condenser. Thereupon the vacuum in the pan 5 is reduced, causing the contacts to separate and thereupon reverse the motor 10. Thus, the 20 valve 9 continues to move between its full open and closed positions and regulates the flow of cooling water and thereby maintains a predetermined vacuum within the pan 5, preferably and usually to within one-quarter inch of water pressure and 25 of substantially constant value.

Adjacent to one side of the chain 11, a double 30 acting switch mechanism indicated at 21 is arranged and is operated by the arm 22 extending in the path of movement of suitable spaced actuating elements 23 applied to the chain 11. In the movement of said chain in one direction, one of the elements 23 actuates arm 22 to open the circuit of motor 10 when the valve 9 is fully closed, while the other of said elements actuates said 35 arm to open the motor circuit when the valve 9 is fully open. Thus, the movements of the valve by the operation of motor 10 are definitely limited.

An additional limit switch indicated at 24 may 40 also be provided to be actuated by suitable means applied to the chain 11 when it is desired to limit the closing movement of valve 9 at some position other than its fully closed position. These switches 21 and 24 are properly connected with 45 the control board 13, and a manually operable switch 25 of any suitable type is provided for the purpose of short-circuiting the switch 24 when it is desired to manually operate the control means.

50 In Fig. 2 of the drawing, we have shown an alternative form of the control device which in certain respects is somewhat simpler than that above described, in that the reversible electric motor with the circuit reversing switch mechanism therefor is eliminated. Thus, we may provide a suitably mounted cylinder 26 with a piston 27 reciprocating therein and connected to one end of a short length of a chain or other flexible actuating means 11', which actuates the 55 valve 9 to its open and closed positions. To the other end of this chain, a suitable weight 28 is attached. A pipe 29 extending from a source of compressed air or other fluid is adapted to be connected to the upper end of the cylinder 26 through the medium of any suitable type of valve such as that shown at 30, which in one position 60 supplies the fluid pressure medium to said cylinder and in another position exhausts the same from the cylinder. As herein shown, this valve is of the rotary type, having an arm 31 to which a contractile spring 32 is attached operating to normally hold the valve in a closed position. This valve arm is also pivotally connected to the core of a solenoid 33, the circuit of which is connected through the switch mechanism 19' and

control board 13' with the source of current, said circuit being opened and closed by the vacuum gauge 15' similar to that above described. In this case, the circuit of the solenoid 33 is normally closed to connect the fluid pressure supply pipe 29 through the valve 30 with the upper end of cylinder 26, thus forcing the piston 27 downwardly and moving valve 9 to its open position. As the vacuum in pan 5 increases to the predetermined value, the circuit closing contact members on the gauge hands are finally brought into engagement with each other, which operates switch mechanism 19' to open the circuit of solenoid 33. When said circuit is thus opened and the solenoid deenergized, spring 32 acts to move the valve 30 to the position illustrated in the drawing, thereby closing the connection between the cylinder 27 and supply pipe 29 and opening communication between the upper end of said cylinder and the atmosphere, so that the air or other pressure medium will be exhausted therefrom as the weight 28 moves downwardly and through the chain 11' operates valve 9 towards its closed position, thereby reducing the supply of cooling water to the condenser. Should 130 the vacuum in the pan 5 again build up to the predetermined maximum before the pressure fluid is completely exhausted from cylinder 26, the gauge contacts will again be brought into engagement with each other to exhaust the air or 135 other fluid from said cylinder. It will, of course, be understood that as soon as the vacuum in the pan is reduced to any appreciable extent below the predetermined maximum, the gauge contacts will be disengaged from each other and the 140 circuit of solenoid 33 again closed so that the supply valve for the cooling water will never move to its fully closed position while the device is in operation. If it is desired to limit the opening movement of valve 9 to a position less than 145 the maximum opening thereof, the limit switch 24' similar to that above referred to may be used and connected in the circuit of solenoid 33.

From the foregoing description considered in connection with the accompanying drawing, the 150 construction and manner of operation of the several illustrated embodiments of the device will be readily understood. It will be seen that in both of the described constructions, the device will operate in a very positive and reliable manner to automatically control or regulate the vacuum, eliminating the necessity of frequent manual attention for this purpose, with a corresponding saving of labor and a higher standard of quality production in the product, due to maintenance of a constantly uniform vacuum. Also, it will be evident that such a device will effect a desirable economy in the use of water in the operation of the condenser. We have herein illustrated and described several simple and practical embodiments of our present improvements, nevertheless, it is to be understood that in so far as the essential features thereof are concerned, the device may also be produced in various other alternative structural forms, and we accordingly 165 reserve the privilege of resorting to all such legitimate changes therein as may be fairly incorporated within the spirit and scope of the invention as claimed.

We claim:

1. An automatic regulator for vacuum producing condensers comprising a valve controlling the supply of cooling water to the condenser, electrically controlled means connected with and operating said valve to its open and closed posi-

- 5 tions, and adjustable means directly influenced by the vacuum governing the current supply to said electrically controlled means to thereby variably position said valve and maintain a predetermined vacuum of substantially constant value. 50
- 10 2. An automatic regulator for vacuum producing condensers comprising a rotary valve controlling the supply of cooling water to the condenser, electrically controlled means for operating said valve to its open and closed positions, and a gauge directly responsive to the vacuum and having contact means governing the supply of current to said electrically controlled means 80
- 15 to operate the valve and thereby maintain a vacuum of substantially constant value. 85
- 20 3. An automatic regulator for vacuum producing condensers comprising a rotary valve controlling the supply of cooling water to the condenser, means for positioning said valve to regulate the continuous flow of cooling water to the condenser including a reversible electric motor, and means comprising a gauge directly responsive to the vacuum and having contact 90
- 25 means governing the supply of current to said motor to thereby adjust said valve between its open and closed positions and regulate the continuous flow of cooling water to the condenser in accordance with the predetermined vacuum 100
- 30 value to be maintained. 105
- 35 4. An automatic regulator for vacuum producing condensers comprising a valve controlling the supply of cooling water to the condenser, means for positioning said valve to regulate the continuous flow of cooling water to the condenser including a reversible electric motor, means comprising a gauge directly responsive to the vacuum and having contact means governing the supply of current to said motor to 110
- 40 thereby position said valve and regulate the continuous flow of cooling water to the condenser in accordance with the predetermined vacuum value to be maintained, and additional switch means actuated by a part of the valve operating 115
- 45 means to open the motor circuit independently of the vacuum gauge and limit movement of the valve towards its open and closed positions. 120
